By his Attorney Henry B. Salisbury

UNITED STATES PATENT OFFICE.

FREDERICK WIELAND, OF BROOKLYN, NEW YORK.

SPINNING-TOP.

SPECIFICATION forming part of Letters Patent No. 792,640, dated June 20, 1905.

Application filed November 8, 1904. Serial No. 231,915.

To all whom it may concern:

Be it known that I, FREDERICK WIELAND, a citizen of the United States, and a resident of the borough of Brooklyn, in the county of 5 Kings and State of New York, have invented certain new and useful Improvements in Spinning-Tops, of which the following is a specification.

My invention relates to spinning-tops, and 10 more particularly to that class which has its spinning-cord secured to the top, a top which may also be moved from place to place, suspended by the cord, while spinning, and also may be rewound by action of the spinning-top. 15 These and other details and objects of my invention are more fully described in connection with the accompanying drawings.

In the drawings like reference characters refer to the same parts in the various figures.

20 Figure 1 is a side view of my improved self-winding top. Fig. 2 is a vertical sectional view. Fig. 3 is a horizontal sectional view at about the middle of the top. Fig. 4 is an enlarged detail view of the spindle and swivel 25 to which the spinning-cord is secured.

The preferred form of top, as shown in the drawings, is a shell of thin metal, comprising two parts 5 and 6 with a telescopic joint, as at 7, where it will be seen that the edge of the 30 upper section 5 fits over the edge of section 6 and is turned under, effectually uniting them. At this point of union is also secured a weighted ring 8, with an outer peripheral flange 9, over which the edges of the sections 35 lock to hold the ring in place, while retaining each other. Vertically situated within the shell of the top is a sleeve 10, bearing on washers 11 and 12 and stiffening the shell, so as to prevent the collapse of same. With-

40 in the sleeve 10 is a second sleeve 13, whose lower end passes through section 6 and is flanged around a washer 14, while its upper end passes through the upper section and has a washer 15 forced upon it to hold the shell 45 and these sleeves firmly together. Tightly secured within the sleeve 13 is the spindle 16, carrying on its lower end the loose handle 17, while its upper end is reduced and headed, as at 18 in Fig. 4. On this reduced end is

placed a swivel 19, in which an indentation 50 20 has been made to prevent it passing over the head, while it is free to rotate independent of the spindle and top. The upper end of the swivel is provided with a loop or hook 21, to which the spinning-cord 22 is secured. 55 The lower end of the spindle 16 is headed to retain the handle thereon. The upper end of the sleeve 13 is provided with fingers 23, which receive and engage the cord when it is to be wound upon the outer end of the sleeve 60 13. The cord may carry a ring 24 or other suitable device to afford means for the operator to securely grasp the cord.

In the act of spinning this top the handle 17 is held in one hand while the cord is slightly 65 wound upon the outer end of the sleeve 13, the fingers 23 engaging the cord and preventing the swivel 19 from moving independently of the top and sleeve. A slight pull upon the cord will then cause the top and sleeve to rapidly revolve, winding up the entire cord upon the sleeve 13. When the entire cord has been wound, it is then suddenly pulled from the sleeve until completely unwound and its strain is wholly upon the swivel. The top is then 70 75 spinning rapidly, held and supported by the handle 17, which may be released, suspending the spinning-top by the cord alone. The lower end of the spindle may be allowed to rest upon the floor, table, or wherever desired. The 80 swivel 19 being free, there is no tendency to twist the cord nor does the latter impede the momentum of the top, although secured to it.

It is obvious that I may modify the construction of this top by making the body of 85 a solid piece of wood or other suitable material providing it with the necessary weight. The handle 17 may also be made of wood, and other minor changes may be resorted to without departing from the spirit of the invention 90 as illustrated.

Having described my invention, what I claim as new, and desire to secure by Letters Patent, is—

1. In a spinning-top, the combination with 95 a weighted top-body, of a spindle passing through the top-body, a handle loosely carried on the lower end of the spindle, and a loop

swiveled on the upper end of the spindle to receive the cord, substantially as described for the purposes set forth.

2. In a spinning-top, the combination with 5 the top-body, of a weighted ring on the top-body, a spindle passing through the top, secured thereto and headed at each end; a loose handle carried on the lower end of the spindle, a loop swiveled on the upper end of the 10 spindle and a cord secured to the loop or hook, substantially as described for the purposes set forth.

3. In a spinning-top, the combination with 15 the top-body composed of two similar sections united at about its middle, a weight secured at the point of union, a sleeve bracing the two

sections, a second sleeve within the bracing-sleeve and passing to the exterior, fingers on the outer end of the second sleeve, a spindle within and secured to the second sleeve and 20 having a reduced end, a loop swiveled to the said reduced end, a cord secured to the loop and a handle loosely carried by the lower end of the spindle, substantially as described for the purposes set forth. 25

Signed at New York, in the county of New York and State of New York, this 5th day of November, A. D. 1904.

FREDERICK WIELAND.
